Frank D. Gray
ATTORNEY.

Patented Nov. 27, 1928.

Des. 76,986

UNITED STATES PATENT OFFICE.

JEDDIA B. CLARK, OF DUNKIRK, INDIANA, ASSIGNOR TO THE INDIANA GLASS COMPANY, OF DUNKIRK, INDIANA, A CORPORATION OF INDIANA.

DESIGN FOR A TUMBLER OR SIMILAR ARTICLE OF MANUFACTURE.

Application filed September 24, 1928. Serial No. 28 254 Term of patent 7 years.

To all whom it may concern:

Be it known that I, JEDDIA B. CLARK, a citizen of the United States, and a resident of the city of Dunkirk, in Jay County and State of Indiana, have invented a new, original, and ornamental Design for a Tumbler or Similar Article of Manufacture, of which the following is a specification, reference being had to the accompanying drawing, forming part thereof.

Figure 1 is a perspective view, and Figure 2 is a transverse section taken on the plane indicated by the line 2—2 of Fig. 1, showing my design.

I claim:

The ornamental design for a tumbler or similar article of manufacture.

Dated at Dunkirk, Indiana, this 10th day of September, 1928.

JEDDIA B. CLARK.
